US00D748297S

(12) **United States Design Patent**
Ma et al.

(10) **Patent No.:** US D748,297 S
(45) **Date of Patent:** ** Jan. 26, 2016

(54) **LED BULB**

(71) Applicant: **BONSHINE OPTICAL ELECTRON TECHNOLOGY CO., LTD.**, Suining, Sichuan Province (CN)

(72) Inventors: **Wenbo Ma**, Suining (CN); **Qiurong Liao**, Suining (CN); **Jianquan Wang**, Suining (CN); **Li Liang**, Suining (CN)

(73) Assignee: **BONSHINE OPTICAL ELECTRON TECHNOLOGY CO., LTD.**, Suining (CN)

(**) Term: **14 Years**

(21) Appl. No.: **29/491,978**

(22) Filed: **May 27, 2014**

(30) **Foreign Application Priority Data**

Dec. 2, 2013 (CN) 2013 3 0593387

(51) LOC (10) Cl. **26-04**

CLAIM

The ornamental design for a LED bulb, as shown and described.

DESCRIPTION

FIG. 1 is a front view of the LED bulb, the rear view being identical to the front view;

FIG. 2 is a side view thereof, the left side view and the right side view being identical;

FIG. 3 is a top view thereof; and,

FIG. 4 is a perspective view thereof.

The broken lines depict environmental subject matter only and form no part of the claimed design.

1 Claim, 4 Drawing Sheets
